REVOLVING SHELF

Charlie Gritton, Skidmore, Tex.

Application March 20, 1939, Serial No. 263,023

4 Claims. (Cl. 211—144)

The present invention relates to new and improved store shelves and more particularly to shelves of the revolving type.

An important object of the invention resides in the provision of a system of shelves whereby facility in reaching articles supported thereon is readily accomplished.

A further object is to provide a system of revolving shelves that provides additional storage space, permits a rapid and efficient dispensing of the merchandise supported thereon, and represents a material time and labor saving device due to the convenient location of the shelves.

15 The invention will be fully and comprehensively understood from a consideration of the following detailed description when read in connection with the accompanying drawing which forms a part of the application.

20 In the drawing:

Figure 1 is a front elevational view, partly in section, illustrating a system of rotary shelves embodying the features of the present invention.

25 Figure 2 is a sectional view taken substantially on line 2—2 of Figure 1.

Figure 3 is a fragmentary vertical sectional view of the supporting means for the shelves, and

30 Figure 4 is a horizontal sectional view taken substantially on line 4—4 of Figure 1.

Referring to the drawing for a more detailed description thereof, there is disclosed a supporting base 5 bolted or otherwise secured by means 6 to a flooring 7, said plate forming a bearing surface for the means which supports the shelves and permits the same to be revolved. Referring more particularly to Figure 3 of the drawing, it will be noted that there is provided a tapered spindle 8 supported centrally of the plate 5 and attached thereto by any desired means. A cylindrical shaped hub 9 surrounds the spindle 8 and is supported on suitable bearings 10 carried by said spindle whereby said hub is free to rotate with the spindle serving as an axis. The upper end of the hub 9 is exteriorly threaded as indicated at 11 for receiving a capping plate 12 having annular portions 13 projecting beyond said hub. A shaft 14 is formed integral with the capping plate 12 and extends upwardly therefrom through the shelf structure generally designated by the numeral 15. The lowermost shelf 16 is bolted as indicated at 17 to the annular portions 13 of the capping plate 12. By this construction, it

will be readily apparent that the shaft 14 and shelf 15 will revolve with the hub 9 about the spindle 8.

The shaft 14, as afore indicated, extends upwardly and forms the supporting means for the multiplicity of spaced shelves 18. The upper end of the shaft 14 extends through the ceiling 19 and rotates within a conventional ball bearing 20.

The multiplicity of shelves 18 are supported about the shaft 14 and preferably decrease in diameter to present a tapered appearance with the topmost shelf 21 being considerably less in diameter than the lowermost shelf 16. Each of the shelves is provided with partitioning members 22 extending circumferentially of the shelves and mounted in spaced relation thereon to provide individual compartments for supporting the merchandise. The partitioning members 22 also serve as a supporting means for the adjacent 20 shelf and therefore materially strengthen the superposed structure of shelves.

Spaced strips of material 23 are secured to the periphery of each of the shelves 18 extending from the topmost shelf 21 to the lowermost shelf 16 and are substantially in line with the partition members 22. Gripping handles 24 are carried by each of the strips 23 and are adapted to be engaged for revolving the shelves.

It is to be understood that the shelves 18 may be of any desired shape and are herein illustrated and described as being circular. Each of the shelves have a central opening for frictionally receiving the shaft 14.

When using the revolving shelves in a store 35 for dispensing merchandise, they are disposed in close proximity to a serving counter. When serving a customer, the clerk may remain in a substantially fixed position and dispense various articles of merchandise from the revolving 40 shelves. The clerk can readily reach and remove a greater number of articles from the shelves from a given point than with the ordinary longitudinal wall shelves thereby speeding up service and acting as a labor saving device. 45

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described and, 55

therefore, such changes and modifications may be made therein as do not affect the spirit of the invention nor exceed the scope thereof as expressed in the appended claims.

5. What is claimed is:

1. A revolving shelf device comprising, a tapered spindle extending from a supporting base, a housing rotatably mounted on roller bearings carried by said spindle, a cap member secured to 10 said housing, a shaft extending vertically of said cap member and rotatable therewith, and a plurality of shelves disposed on said shaft and supported in spaced relation thereon.

15. A revolving shelf device comprising, a tapered spindle extending from a supporting base, a housing rotatably mounted on roller bearings carried by said spindle, a cap member secured to said housing, a shaft extending vertically of said cap member for rotation with said housing, a first shelf disposed about said shaft and secured to 20 said cap member, and a plurality of shelves disposed in spaced relation above said first mentioned shelf and supported on said shaft.

20. A revolving shelf device, comprising, a tapered spindle extending from a supporting base, a housing rotatably mounted on roller bearings carried by said spindle, a cap member secured to 25

said housing, a shaft extending vertically of said cap member for rotation with said housing, a first shelf disposed about said shaft and secured to said cap member, and a plurality of shelves disposed in spaced relation above said first mentioned shelf and supported on said shaft, said shelves decreasing in diameter upwardly with the topmost shelf of a lesser diameter than the lowermost shelf, and partition members carried by each of said shelves.

5. A revolving shelf device comprising, a tapered spindle extending from a supporting base, a housing rotatably mounted on roller bearings carried by said spindle, a cap member threadedly attached to said housing, said cap member having annular portions projecting beyond said housing, a shaft extending vertically of said cap member for rotation with said housing, a first shelf disposed about said shaft and secured to the annular portion of said cap member, and a plurality of shelves disposed in spaced relation above said first-mentioned shelf and supported on said shaft, said shelves decreasing in diameter upwardly with the topmost shelf of a lesser diameter than the lowermost shelf.
